UNITED STATES PATENT OFFICE.

HENRY CLAY WADE, OF NEW YORK, N. Y., ASSIGNOR TO AQUA GAS COMPANY, OF NEW YORK, N. Y., A CORPORATION OF DELAWARE.

APPARATUS FOR GENERATING GASEOUS FUEL.

1,121,695.

Specification of Letters Patent. Patented Dec. 22, 1914.

Application filed February 25, 1913. Serial No. 750,497.

To all whom it may concern:

Be it known that I, HENRY CLAY WADE, a citizen of the United States, residing at New York city, borough of Manhattan, in the county of New York and State of New York, have invented certain new and useful Improvements in Apparatus for Generating Gaseous Fuel, of which the following is a specification.

10 My invention relates to an apparatus for generating gaseous fuel, which fuel may be burned as made, or stored in a tank for subsequent use, and will be understood by reference to the accompanying drawings, in which—
15 Figure 1 is a view in elevation, partly in section, of a structure embodying one form of my invention; Fig. 2 is a central vertical section of a combined generator and burner, being the upper part of Fig. 1; Fig. 3 a 20 top plan view of Fig. 2, partly in section; Fig. 4, a section on the plane of the line 4—4 of Fig. 2; and Fig. 5, a section on the plane of the line 5—5 of Fig. 3.

Similar reference numerals indicate similar parts in the several views.

Referring to the drawings, the numeral 1 designates a tank divided by partitions 2 and 3 into compartments 4, 5 and 6. The compartment 4 serves as a receptacle for a 30 gaseous or liquid fuel containing carbon to be utilized or vaporized; compartment 5 as a receptacle for water; and compartment 6 as a storage tank for the generated gas, should it be desired. In the partition 2 is 35 an opening 7 establishing communication between the compartments 4 and 5. The tank may be provided with an oil gage for compartment 4, and a pressure gage for compartments 4 and 5, as indicated in Fig. 1.

40 The gas generator comprises a cup-shaped base 8 provided on its inner face with an annular seat 9 to receive an annular burner 10. The generator proper is in the enlarged upper section 11 integral with the base, or 45 separate therefrom and secured thereto by any suitable means. The generator section is substantially cylindrical with its inner wall flaring outward and upward from the seat 9, and completely surrounds the burner 50 10. Within the section 11 are formed two chambers 12 and 13, separated by a web 14, said chambers extending as far as may be desired through and around the body of section 11. As shown, the chambers 12 and 13

are substantially annular, the ends being 55 separated by short webs.

Leading from water compartment 5 of tank 1 is a pipe 15, which pipe, by a suitable connection, discharges into the chamber 12 at one end thereof, and leading from 60 the other end of said chamber is a pipe 16, which latter pipe, through a suitable connection, is led into chamber 13 at one end thereof. Leading from the compartment 4 of tank 1 is a pipe 17, which pipe is fitted to 65 the connection between pipe 16 and chamber 13, as shown in Figs. 2 and 3. Leading from the other end of chamber 13 is a pipe 18 connecting said chamber with an expansion chamber the latter preferably in the 70 form of a vertically disposed hollow cylinder 19 forming part of, and depending from, the base 8. The lower end of the expansion chamber is closed by a plug 20 threaded into the shell thereof, the plug carrying 75 a stem 21 which extends longitudinally of the shell and terminates immediately below an opening 22 in the base 8.

Threaded into the opening 22 is a nozzle 23 having a longitudinal channel 24. The 80 lower end of the nozzle is flared outwardly to provide a chamber 25, and said lower end is closely approached by the upper end of stem 21. Communication is established between the interior of the expansion chamber and the bore of the nozzle by means of 85 grooves 26 in said stem, the upper ends of the grooves opening into chamber 25.

Coiled about the stem 21, and substantially filling the chamber 19, is a sheet of 90 wire gauze 27, preferably, although not necessarily, of brass, extending from end to end of said chamber and abutting the upper wall of said chamber and the plug 10. The wire gauze being highly heated by conduction, serves to further expand the gas and to strain out any mechanical impurities which may be carried over.

Surrounding the base of chamber 19 is a receptacle 28 to receive liquid fuel, such as 100 alcohol, which may be burned to heat the generator when started.

The annular burner 10 has a central passage or opening 29 vertically in line with and above the outlet end of nozzle 23, so 105 that the gas emitted from the nozzle passes upward through said passage or opening into the space 30, formed by the wall 31 and

the cap or flame-plate 32. The latter has a plurality of flame jet nozzles or openings 33 in the crown thereof, and similar nozzles or openings 34 in the side wall to direct the 5 flame against the inner wall of the generator, so that the chambers 12 and 13 may be heated to a relatively high temperature.

The operation of the above-described apparatus is as follows, assuming that a 10 hydrocarbon liquid is to be used. Any suitable means may be employed to feed the water and hydrocarbon liquid to the chambers 12 and 13, respectively. In Fig. 1 is shown an air force-pump 35 connected to 15 the oil compartment 4 of tank 1, the opening 7 in partition 2 admitting the air under pressure into the water compartment 5. Sufficient pressure is maintained upon the 20 surfaces of the water and oil to feed them to the generator chambers through the pipes 15 and 17, respectively, valves 36 in said pipes controlling the supply. The apparatus may be started by burning a liquid fuel, such as alcohol, in cup 28, the flame 25 passing upward and enveloping the generator and heating the same sufficiently to vaporize the liquid hydrocarbon which may be in chamber 13. The vaporized oil is conducted through pipe 18 to expansion chamber 30 19, and thence, through nozzle 23, to burner 10, where it is ignited. When the generator is sufficiently heated, the water in chamber 12 will be converted into steam, and, as the temperature of the walls of the 35 generator, and of chambers 12 and 13, is increased as the vaporization of the oil and generation of gas becomes more active and the heat more intense, the steam generated in chamber 12 passes therefrom into outlet 40 pipe 16; and, in so doing, is brought into contact with any suitable material capable, under the high heat generated therein, of increasing the temperature of the steam to thereby facilitate its decomposition in the 45 presence of the hydrocarbon.

The material used, and that preferred by me, is platinum gauze, which may be conveniently placed, as at 37, in the opening of the section 11 of the generator adapted to 50 receive the end of pipe 16. That is, the platinum gauze is practically located in chamber 12, the means shown being a feasible way of supporting and confining it so that it may be readily inserted in place, and 55 renewed if necessary. The highly heated steam flows through pipe 16 to the upper chamber 13 meeting, as it enters said chamber, the oil delivered through pipe 17. The hydrocarbons passing into the heated chamber 60 13 are broken up and would ordinarily deposit a part of their carbon, but this heated carbon in contact with the highly heated steam decomposes the latter, forming carbon-monoxid and setting free the hydrogen. 65 These gases mingle with the hydrocarbon

vapors evolved from the oil and flow through pipe 18 to chamber 19 where the gases and vapor are thoroughly mixed and further expanded, the mixture flowing through grooves 26 into nozzle 23. The 70 pressure under which the mixture leaves the nozzle directs it through the central passage 29 to the space 30 of the burner, from which it escapes and is ignited through the 75 openings 33 and 34. The flame issuing from the openings 34 is directed against the inner wall of the generator for the purpose of converting the water into steam, for heating the platinum gauze, and for vaporizing the 80 hydrocarbon liquid in chamber 13 and for decomposing the steam therein.

By placing the burner within the generator, as shown, the heat necessary to effect the generation and decomposition of the steam, and the vaporization of the oil, may 85 be readily attained, more particularly from the heat of the flame issuing from the lower set of openings 34. The air necessary for complete combustion is admitted through openings 38 in base 8. If desired, a portion 90 of the gas generated may be conducted by pipe 39 to compartment 6 of tank 1, or to any other suitable storage tank, from which it may be drawn.

What I claim and desire to secure by Letters Patent of the United States is:—

1. In an apparatus of the character described, a generator comprising a base, an upper section within which two annular chambers are formed, means for delivering water to one of said chambers wherein it is converted into steam, means for delivering the steam to the second of said chambers, means for delivering a hydrocarbon to said second chamber wherein it is vaporized and the steam decomposed, a burner supported upon said base, and means for delivering the gas to the burner. 100

2. In an apparatus of the character described, a generator comprising a base, an upper section within which two chambers are formed, means for delivering water to one of said chambers wherein it is converted into steam, means for delivering the steam to the second of said chambers, means for delivering a hydrocarbon to said second chamber wherein it is vaporized and the steam decomposed, a burner, means for delivering the gas to the burner; and a body having high heat absorbing capacity intercepting the flow of steam and located between said chambers. 110 115

3. In an apparatus of the character described, a burner, a generator surrounding said burner and adapted to be heated thereby, said generator having two chambers, means for delivering water to one of said chambers wherein it is converted into steam, a pipe for delivering the steam to the second of said chambers, means for delivering a 120 125 130

hydrocarbon to said second chamber wherein it is vaporized and the steam decomposed, an expansion chamber connected to said second generator chamber, and means for delivering the mixture from the expansion chamber to the burner.

4. In an apparatus of the character described, an annular burner, an annular generator surrounding said burner, the latter having flame nozzles or openings to direct the flame against the inner wall of the generator, said generator having two chambers, means for delivering water to one of said chambers wherein it is converted into steam, a pipe for delivering the steam to the second of said chambers, means for delivering a hydrocarbon liquid to said second chamber wherein it is vaporized and the steam is decomposed, and means for delivering the gases and vapor to the burner.

5. In an apparatus of the character described, a burner, a generator surrounding said burner and adapted to be heated thereby, said generator having two chambers, means for delivering water to one of said chambers wherein it is converted into steam, a conduit for delivering the steam to the second of said chambers, means for deliver-

ing a hydrocarbon to said second chamber wherein it is vaporized and the steam decomposed, means for delivering the mixture to the burner, and means to aid in raising the temperature of the steam, said means intercepting the flow of steam and absorbing heat from the burner.

6. In an apparatus of the character described, a burner, two chambers subjected to heat from the burner, means for delivering water to one of said chambers wherein it is converted into steam, a conduit for delivering the steam to the second of said chambers, means for delivering a hydrocarbon to said second chamber wherein it is vaporized and the steam decomposed, to aid in raising the temperature of the steam consisting of a body having high heat absorbing capacity intercepting the flow of steam and located between said chambers.

In testimony whereof I have hereunto signed my name in the presence of two subscribers.

HENRY CLAY WADE.
